RADIAL BEAM MODULATOR TUBE

Carl C. Bath, Baltimore, Md., assignor to Bendix Aviation Corporation, Towson, Md., a corporation of Delaware

Application October 28, 1947, Serial No. 782,641

7 Claims. (Cl. 250—27.5)

1

This invention relates to vacuum tubes for use in pulse-time modulated communications systems, and more specifically it relates to a radial beam modulator tube for use in multi-channel pulse-modulated systems.

In prior art multiplexing systems, conventional vacuum tubes were used. This resulted in many disadvantages, such as, for example, the necessity of using several tubes for each channel utilized, in addition to the tubes used in the master synchronizing circuits. Each channel also required some means of amplitude limiting to prevent over-modulation, and the consequent cross talk.

Many attempts have been made, in the past few years, to develop a tube to eliminate these shortcomings of pulse-time modulated multiplex systems. These developments, however, have not solved the problem, and the resultant tubes are bulky, fragile, and costly.

It is an object of this invention to provide a radial beam modulator tube that will be more efficient than tubes now known to the art.

It is a further object to provide a tube which functions to permit greater time displacement of the channel pulses without increasing the possibility of cross talk.

It is a further object to provide a tube that is smaller, more rugged and cheaper to produce than those known to the present art.

The above objects and advantages have been accomplished by devices embodying the instant invention.

Fig. 1 is a diagrammatic view in cross section illustrating the position of the various elements in a tube embodying the instant invention;

Fig. 2 is a plan view of a tube of the type shown in Fig. 1;

Fig. 3 is a cutaway side view of the tube of Fig. 2, taken along the line 2—2 of that figure.

Fig. 4 is a view of the window plate element 13 in an "unrolled" position illustrating the placement of the channel and marker slots, and

Fig. 5 is a view similar to Fig. 2, illustrating the position of the two beams and their direction of rotation together with a circuit arrangement by which they can be formed.

Referring to the drawing, in particular Figs. 1, 2, 3, and 4, a radial beam modulator tube, in accordance with this invention is shown comprising a cylindrical cathode element 10, enclosed by a circular accelerating anode 11, which is provided with a centrally located circumferential slot 23. Extending outwardly in a horizontal plane, but not physically contacting the lower-most portion of the accelerating anode 11, are a

plurality of deflector plates 12, even in number, but so arranged as though there were an odd number, that is, each plate is diametrically opposed by a space. The plates are equally spaced with the exception that at one point of the circle a plate is omitted. Surrounding the deflector plates 12, is a "window" plate 13, cylindrical in form and incorporating slots, each of which is radially coincident with a respective one of the plates 12 and is disposed at an angle with respect to the axis of the cathode 10. At the point where there is no deflector plate there is a wider slot 25 which extends parallel to the axis of the cathode 10. Surrounding the window plate 13 is a set of collector plates 14, each located just outside of a respective slot 24 in the window plate 13, all being connected to one another electrically.

When the cathode 10 is heated by a suitable source, it emits electrons. When a positive voltage is applied to the accelerating anode 11, the electrons emitted from the cathode 10 are attracted thereto. Due to the velocity built up by the electrons traveling toward the accelerator 11, some of the said electrons pass through the horizontal slot 23 in the accelerator anode in a plane perpendicular to the axis of cathode 10. The result, if no further forces were acting on the electron stream, would be the forming of an electron "disc." In operation, however, as shown in Fig. 5, the tube is mounted within a rotating magnetic field generated for example, by two sets of coils 15, 16 and 17, 18 positioned at right angles to each other and fed with quadrature currents from a source 19, by way of a phase splitting network comprising a condenser 20 and a resistor 21. The result is to concentrate the electrons into two sharply defined "beams," diametrically opposite each other and rotating around the axis of the cathode 10, as illustrated in Fig. 5, at a uniform rate, which is determined by the frequency of the alternating currents in the magnetic field coils. For standard communication systems, the frequency should be between 4000 and 5000 cycles per second. The said beams pass over the deflector plates 12 before reaching the window plate 13, and due to the "odd" disposition of the deflector plates 12, only one beam is over a deflector plate at any given time. When one beam has reached the trailing edge of a deflector plate, the opposite beam is about to reach the leading edge of another deflector plate, as illustrated in Fig. 5, in which the reference numeral 22 indicates the electron beam traveling the direction indicated by the arrows. Signal voltages from several communication

channels are applied to the deflector plates 12, which tends to raise or depress the beams as they pass over the said plates, depending on the polarity and amplitude of the voltage on the plate at the time the beam is passing.

The slots 24 in the window plate 13 are cut at an angle to the axis of the cathode 10, as illustrated in Fig. 4. If the beam is raised or depressed it will strike the slot at a different time than if it were traveling perpendicular to the axis of cathode 10. This is the method used to obtain pulse time modulation. The electrons which pass through the slots 24 in the window plate 13, are collected by the anodes 14 which are mounted adjacent to each slot. These collector anodes 14 are joined together electrically and connected to an external load circuit, so the electrons passing through the slots in the window plate 13 cause negative voltage pulses to be present on the collector anode 14. The individual channel pulses are time modulated in accordance with the signal voltages applied to the individual deflecting plate 12. The wide slot 25 in the window plate 13, positioned in the space which has no deflecting plate, generates a wide unmodulated pulse for synchronization purposes.

If a signal, too large in amplitude, is applied to a deflector plate 12, the beam will be driven beyond the end of the slot in window plate 13, and the pulse will be momentarily removed. This will cause peak clipping of the modulating signal, but it cannot result in cross-talk or spillover into adjacent channels, and due to this, the instant invention is self limiting.

It is quite feasible to add another accelerating anode concentric with the accelerating anode 11, to obtain a still sharper focusing of the beam.

While the drawings illustrate the present invention with 8 deflector plates and a window plate with a corresponding number of windows, it is to be understood that there can be employed any even number desired up to about 24. The marker slot in the window plate can be other than one wide slot as illustrated in the drawings, for example, two narrow slots parallel to each other can be used, so long as an unmodulated pulse can pass.

Furthermore, the collector anodes, by the use of suitable material, understood by those skilled in the art, can be used as secondary emitters, thus, using the window plate as the collector.

What is claimed is:

1. A radial beam modulator tube comprising: a cylindrical cathode; an accelerating anode surrounding said cathode and being formed with a circumferential planar slot; a plurality of deflector plates positioned in a common plane offset from the plane of said slot and extending normally to the axis of said cathode, said deflector plates being mounted in a circle about said anode and being equally spaced with each plate diametrically opposed by a space between a pair of said plates, said circle of plates being interrupted by the omission of a plate therefrom; a cylindrical element surrounding said circle of plates and coaxial with said cathode, said element being provided with a plurality of slots, said slots extending at a uniform angle with respect to the axis of said element and each of said slots being located in symmetrical radial coincidence with a respective one of said plates, said element being provided with a slot extending parallel to the axis thereof and located in radial coincidence with said interruption in said circle of plates, and a plurality of collector plates,

each located outside of said element and in radial coincidence with a respective one of said slots, said collector plates being connected together electrically.

5. 2. A radial beam modulator tube as claimed in claim 1, including means adjacent said tube for producing a magnetic field within said tube.

3. A radial beam modulator tube comprising a cathode, means adjacent said tube for forming the electrode stream from said cathode into a beam extending diametrically of said tube and rotatable about said cathode, a plurality of spaced deflector plates disposed with their major surfaces in parallelism with the path of said beam, each 10 of said plates being diametrically opposite a space between adjacent plates so that a plane defined by said beam and extending normal to said plates will intersect only one of said plates at a time as said beam rotates, and anode means disposed in radial coincidence with each of said plates for intercepting said electron stream.

4. A radial beam modulator tube comprising a cathode, means adjacent said tube for forming the electrode stream from said cathode into a beam extending diametrically of said tube and rotatable about said cathode, means adjacent the path of said beam for sequentially applying deflecting forces to alternate ends of said beam as it rotates, a plurality of spaced anode elements 25 for said beam, each of said anode elements being positioned in said path to intercept said beam during the application of one of said deflecting forces thereto, and means between said cathode and said anode elements for varying the time at which interception of said beam by each of said anode means occurs, said variation being a function of the deflecting forces applied while said beam and said anode means are radially coincident.

5. A radial beam modulator tube comprising a cathode, means adjacent said tube for forming the electron stream from said cathode into a beam extending diametrically of said tube and rotatable about said cathode, a plurality of spaced deflector plates disposed with their major surfaces in parallelism with the path of said beam, each 40 of said plates being diametrically opposite a space between adjacent plates so that a plane defined by said beam and extending normal to said plates will intersect only one of said plates at a time as said beam rotates, anode means disposed in radial coincidence with each of said plates for intercepting said electron stream, and apertured masking means located between said cathode and said anode means.

6. A radial beam modulator tube comprising a cathode, means adjacent said tube for forming the electrode stream from said cathode into a beam extending diametrically of said tube and rotatable about said cathode, means adjacent the path of said beam for sequentially deflecting alternate ends of said beam in lateral directions from its path of rotation, a plurality of anode means positioned in the path of said beam to intercept said beam during each of said lateral deflections, and an apertured masking means located between said cathode and said anode means, each of the apertures of said masking means being located between said cathode and 65 a respective one of said anode means and shaped to vary the time of interception of said beam by said respective one of said anode means as a function of the lateral deflection of said beam from said path.

7. A radial beam modulator tube comprising a

cathode, means for forming an electron stream into a beam extending diametrically of said tube and rotatable about its central portion, deflecting means adjacent the path of said beam for sequentially modulating alternate ends of said beam by causing lateral deviation thereof from the normal path of rotation, means in the path of said beam for intercepting the modulated portion of the beam during each of said deviations and means between said cathode and said intercepting means for varying the time of said interception in terms of the degree and direction of said lateral deviation.
